[57] CLAIM

The ornamental design for an “electrical ground connector for meter panel”, as shown and described.

DESCRIPTION

FIG. 1 is a right side, top and front perspective view of an electrical ground connector for meter panel, showing our new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a bottom plan view thereof.

The broken line showing in FIGS. 1—6 is included for the purposes of illustrating environmental structure only and forms no part of the claimed design.
